CLAIM

The ornamental design for the multi-function hand tool, as shown.

DESCRIPTION

FIG. 1 is a front view of the multi-function hand tool in an open position.

FIG. 2 is a rear view of the multi-function hand tool in an open position.

FIG. 3 is a left side view of the multi-function hand tool in an open position.

FIG. 4 is a right side view of the multi-function hand tool in an open position.

FIG. 5 is a top view of the multi-function hand tool in an open position; and,

FIG. 6 is a bottom view of the multi-function hand tool in an open position.

The broken line portions of the multi-function hand tool forms no part of the claimed design.
